REFINING PHENOLS

Erik Clemmensen and Roy M. Miller, St. Louis,
Mo., assignors, by mesne assignments, to Mon-
santo Chemical Company, a corporation of
Delaware

No Drawing. Application June 29, 1931
Serial No. 547,790

4 Claims. (Cl. 202—57)

This invention relates to the refining of cresols or phenols or mixtures thereof such as is obtained, for example, from coal tar distillates, and it has particular application to a method of refining crude cresols and/or phenol whereby one is enabled to remove the color imparting properties and thereby obtain a colorless product which is stable even in the presence of strong light for relatively long periods of time.

10 The object of this invention is to provide a method of refining crude phenol of the type described whereby a colorless product capable of resisting discoloration even in the presence of sunlight for relatively long periods of time may be obtained.

15 We have found that by distilling phenol or cresols in the presence of a small amount of inorganic bases, either at atmospheric or sub-atmospheric pressure a colorless relatively light stable product may be obtained.

20 One method of proceeding consists in adding to cresol before or after the phenol has been separated therefrom and which may consist of one or more of the cresol isomers, approximately 1% by weight of soda ash. A slight evolution of carbon dioxide will generally be observed. After agitating the mixture of cresol and soda ash for a short time to insure uniform distribution of the soda ash in the charge and complete reaction with impurities present, the mixture is distilled according to the usual practice. A small amount of residue remains, which consists largely of unreacted soda ash together with a small amount of the salts of coal tar acid impurities.

25 The product is colorless and does not discolor appreciably even after several weeks. Without the addition of the soda ash the distilled product retains a characteristic pink or brown coloration even after repeated distillation and turns a dark red or brown after but a few days.

30 While we have found that the alkali metal carbonates and bicarbonates are particularly well suited, a variety of inorganic bases may be employed, including the alkaline earth metal carbonates and bicarbonates, as well as oxides or hydroxides, the alkali metal hydroxides or the alkali metal and alkaline earth metal salts of weak acids, such for example as, sodium cresylates or phenate, which may be obtained by treating cresol or phenol with caustic soda.

From the foregoing description, it will be apparent that this invention affords a simple and effective means of improving the quality of phenol and cresols, that it does not necessitate the installation of special equipment, nor does it require the supervision of a skilled technician.

45 Although a specific embodiment of the invention is set forth and several modifications have been indicated, it will be apparent that the invention is susceptible to numerable modifications and variations without departing from the substance thereof and we desire, therefore, that it be limited only as indicated in the claims.

50 What we claim is:

1. The method of refining crude phenols which 55 consists in distilling the same after adding thereto a relatively small quantity as compared to the quantity of phenol being treated of an inorganic base.

2. The method of refining crude cresols, which 60 consists in distilling the same after adding thereto a relatively small quantity as compared to the quantity of crude cresol being treated of a material selected from a group consisting of the following: the alkali metal carbonates and hydroxides, the alkaline earth metal carbonates, bicarbonates, oxides, hydroxides, the alkali and alkaline earth metal cresylates and the bicarbonates of the alkali and alkaline earth metals.

3. The method of refining cresols, which 65 comprises distilling the same after adding thereto a relatively small quantity of alkali or alkaline earth metal base as compared to the quantity of cresol being treated.

4. The method of refining cresylic acid that 70 comprises admixing a relatively small quantity as compared to the quantity of acid being treated of alkali metal carbonate therewith and subsequently distilling the cresylic acid.
